ATTORNEY

UNITED STATES PATENT OFFICE.

JULIAN A. GILES, OF WATERTOWN, NEW YORK.

DESIGN FOR AN OIL-GUARD.

SPECIFICATION forming part of Design No. 25,146, dated February 11, 1896.

Application filed October 18, 1895. Serial No. 568,150. Term of patent 3½ years.

To all whom it may concern:

Be it known that I, JULIAN A. GILES, a citizen of the United States, residing at Watertown, in the county of Jefferson and State of New York, have invented a new and useful Design for an Oil-Guard, of which the following is a specification.

My design is for an oil-guard of that class applied in peripheral relation to an engine fly-wheel containing a governor, and for the purpose of catching oil thrown from the governor or other moving part within the fly-wheel.

The design is illustrated in the accompanying drawings, in which similar numerals indicate corresponding parts in all the figures.

Figure 1 is a front or outer face view of an oil-guard embodying my design. Fig. 2 is a central vertical sectional view thereof, and Fig. 3 is a rear or inner face view of the oil-guard.

The leading or most essential feature of my design for oil-guards consists in its general circular or rounding marginal or peripheral contour 1, in connection with a smaller rounded edge outline 2 extending but part way around within the larger marginal contour 1 and merging into two inwardly-projecting edge outlines 3, whereby the guard presents

to the eye the form of a partial annulus or ring 4, with a radial inwardly-projecting prominence 5 lying in the general facial plane of the guard. The bulb-like projection 6 at the extremity of the prominence 5 is not an essential feature of the design. 35

A less important feature of the design consists in radial lug-like prominences 7, which project from the face past the outer periphery 1 of the guard, and have bulbous extremities 8, which may vary more or less in form. 40

As seen from its inner face, the oil-guard presents to the eye a rounded or substantially circular edge outline or contour 9 within the larger marginal contour 1, and removed from the face portion 4, or in rear of the same, 45 while at the inner face of the portion 5 and extending radially outward from its extremity is a rib-like prominence 10, which is a non-essential feature of the design.

What I claim is—

The design for an oil-guard, substantially as herein shown and described.

In testimony whereof I affix my signature in the presence of two witnesses.

JULIAN A. GILES.
